DESIGN FOR A DISPLAY STAND

Harvey F. Jackson, Brooklyn, N. Y.

Application June 20, 1933, Serial No. 48,471

Term of patent 3½ years

To all whom it may concern:

Be it known that I, HARVEY F. JACKSON, a citizen of the United States, residing at the city of New York, Borough of Brooklyn, Kings County, in the State of New York, have invented a new, original, and ornamental Design for Display Stand, of which the following is a specification, reference being had to the accompanying drawing forming a part thereof.

In the drawing—

Fig. 2 is a perspective view looking from the rear, and

Fig. 3 is a top view thereof.

I claim:

The ornamental design for a display stand, as shown.

HARVEY F. JACKSON.
